METHOD AND MEANS FOR BINDING IN WEFT THREADS IN LOOMS FOR WEAVING

Erwin Pfarrwaller, Winterthur, Switzerland, assignor to Sulzer Frères, Société Anonyme, Winterthur, Switzerland, a corporation of Switzerland

Application March 4, 1948, Serial No. 12,948
In Switzerland March 8, 1947

22 Claims.

(Cl. 139—55)

1

The present invention relates to a method and means for binding weft threads in a fabric while it is woven on a loom, by binding threads moving substantially in the direction of the warp threads and being twisted about one another between weft threads, and more particularly to a method and means as aforesaid whereby the direction of rotation of the twists is changed after binding a plurality of weft threads.

It is an object of the present invention to provide a method and means for binding weft threads by pairs or groups of binding or warp threads whereby the threads of one group are twisted about one another and the direction of rotation of the twists is reversed after binding of a predetermined number of weft threads. This improves the binding effect considerably and the bound weft threads are held much faster by using the method and means according to the invention than by using conventional methods and means whereby the direction of rotation of the twists is changed after binding each weft thread as for example in the case of twisting produced by a gauze harness. Since with the new method the direction of twist is not changed after every bound weft thread it is also possible to bind a plurality of weft threads between two twists and a great variety of patterns can be obtained.

A further object of the invention is the provision of a method and means for binding weft threads by a plurality of groups of binding threads whereby the threads of the individual groups are twisted about one another between weft threads to be bound and the direction of rotation of the twists of each group is reversed after binding a predetermined number of weft threads.

Another object of the invention is the provision of a method and means for binding weft threads by a plurality of groups of binding threads whereby the threads of the individual groups are twisted about one another between weft threads to be bound and the direction of rotation of the twists of each group is reversed after binding a predetermined number of weft threads and whereby the points of reversal of rotation of the twists of different groups of binding threads are at different weft threads.

An object of the invention is the provision of a mechanism for twisting binding threads about weft threads in looms for weaving comprising a plurality of twist rings and a mechanism for operating same and deriving its power from a common loom drive, said mechanism being

2

adapted to individually drive said twist rings at different directions of rotation and to change the direction of rotation of different twist rings at different moments.

5 An object of the invention is the provision of a mechanism for twisting binding threads about weft threads in looms for weaving comprising a twist ring operated by a guide mechanism comprising a guide wheel having guide grooves on its circumferential surface and a drive wheel having rollers attached thereto which are adapted to roll in said grooves and to rotate the drive wheel at speeds and periods determined by the shape of said guide grooves. The guide grooves may be 10 made up of individual members which are removably attached to the circumference of the guide or actuating wheel. In this case the individual members can be replaced or changed for others having a differently shaped channel or curve or 15 cam portion whereby a great variety of channel configurations can be obtained with a relatively small number of grooved members.

Another object of the present invention is the provision of a positively controlled binding thread 20 stop motion feeler whereby the periods during which the feeler rides on a binding thread and thereby the extent of its up and down motions are limited.

An object of the invention is the provision of 25 a twist ring construction which takes little space and whereby a great number of rings can be placed side by side and threading is facilitated even with a plurality of twist rings positioned immediately adjacent one another.

30 With the method and means according to the invention a great variety of weaving and binding patterns can be produced by means of simple mechanisms. These mechanisms comprise exchangeable parts for changing the designs or patterns without necessitating major alterations of the mechanisms.

35 Further and other objects of the present invention will be hereinafter set forth in the accompanying specification and claims and shown 40 in the drawings, which by way of illustration show what I now consider to be preferred embodiments of the invention.

In the drawings:

45 Fig. 1 is a diagrammatic front elevational view of a loom according to the invention;

Fig. 2 is a diagrammatic side elevational view illustrating the movement of the threads in a loom according to the invention;

50 Fig. 3 is a diagrammatic top plan view illus-

55

trating the movements of the threads in a loom according to the invention;

Fig. 4 is a sectional view of a thread twisting head the section being taken along line IV—IV of Fig. 2;

Fig. 5 is an enlarged view in axial direction of a part of the twisting head illustrated in Fig. 4;

Fig. 6 illustrates another portion of the device shown in Fig. 4 in larger scale;

Fig. 7 is a diagrammatic illustration of a mechanism for driving the shafts of the twisting rings;

Figs. 8 to 11 illustrate diagrammatically a part of the guide groove portion of a wheel actuating the drive shafts of the twisting rings;

Fig. 12 is a diagrammatic top view of a fabric 15 salvage with threads bound and twisted according to the invention;

Figs. 13 and 14 are large scale radial and axial views, respectively, of a portion of the guide and actuating wheel forming part of the mechanism shown in Fig. 7;

Fig. 13' is a large scale radial view of a portion of a modified guide;

Fig. 15 is a diagrammatic view of a modified twisting produced by the guide shown in Fig. 13';

Fig. 16 is a diagrammatic illustration of a twisting head and controlled binding thread stop motion feeler mechanism;

Fig. 17 is a diagrammatic side elevational view of a mechanism for driving the twist ring shafts with the reversing tooth gears rotating in opposite directions;

Fig. 18 is a sectional view of the mechanism illustrated in Fig. 17, the section being taken along line XVIII—XVIII of said figure;

Fig. 19 is a diagrammatic side elevational view of a modified mechanism for intermittent drive of twisting rings;

Fig. 20 is a diagrammatic side elevation of another modification of a mechanism for driving 40 twist rings according to the invention;

Figs. 21 and 22 are diagrammatic side elevational views of yet another modification of a mechanism for driving the shaft of twist rings, the two figures showing the mechanism in two different operating positions;

Fig. 23 is a side view of the mechanism illustrated in Fig. 22;

Fig. 24 is a diagrammatic side view of a portion of a simplified twist ring mechanism whereby the points of reversal of the direction of twist rotation of different thread groups cannot be staggered.

Like parts are designated by like numerals in all figures of the drawings.

The drive mechanism including a motor for supplying the power thereto of the loom illustrated in Fig. 1 is housed in casing 1. This drive mechanism operates all parts of the loom including main shaft 2 with hand wheel 3, a picking mechanism contained in box 4, a shuttle receiving mechanism disposed in casing 5, a warp beam 6 with warp threads 7, a fabric beam 8 with fabric 9, and heddles 10. The loom is started or stopped by manipulating handles 11 which are rigidly connected with control rod 13. The twisting heads 14 produce twisted selvages at the lateral edges of the fabric, and twisting head 14' produces twistings in the body of the fabric which form selvages in case the fabric is severed therealong. A shuttle 17 is picked by the picking mechanism in box 4 through the shed to the receiving mechanism in box 5 and inserts a weft thread 18 into the shed from a weft spool 19 located outside of the shed.

As obvious from Figs. 2 and 3 the warp threads 7 move from warp beam 6 over a tensioning beam 20 where they separate to form an upper shed 21 and a lower shed 22, through warp stop motion feelers 23, eyes 24 of the heddles 10, and reed 25 to the apex 26 of the shed where they form the fabric 9 by interlacing with the weft threads 18. The fabric passes over a guide beam 27 and is then wound on a fabric beam 8.

Binding threads 28 and 29 move from spools 30 and 31 over the tensioning beam 20, through a binding thread stop motion feeler 32, individually through eyes 33 and 34 of a twisting ring 35, together through space 36 of the reed 25, and to the apex 26 of the shed, wherefrom they are wound, intertwined with fabric 9, on the beam 8.

Spools 30 and 31 may rotate on the same axis or on different axes, as shown. Instead of drawing the binding threads from individual spools, warp threads may be used for binding.

The twisting rings 35 and 72, 73, 74, which are illustrated in Figs. 4, 5 and 6, have ear portions 33' and 34' projecting into the opening of the rings and being provided with eyes 33 and 34, respectively are supported in bearings 37' in frame 37. The rings are provided with teeth 38 and individually engage the teeth of pinions 39 and 40. The latter are keyed to shafts 41 and 42, respectively, which are driven by the guide wheel 43 and a mechanism illustrated in Fig. 7. Bevel gears 102 and 102' transmit the rotation of shafts 101 and 101' to shafts 41 and 42 respectively. Shaft 101 is provided with a gear wheel 46 which is engaged by gear wheel 44 whose axis of rotation is at a right angle with respect to that of guide wheel 43 and which is provided with cam rollers 44' adapted to engage guide grooves on the circumferential surface of wheel 43. Shaft 101' is driven in like manner as 101 there being instead of the single wheel 46 a gear 46' which is driven by wheel 45 whose cam rollers 45' are also adapted to engage the grooves on wheel 43. The cooperation of wheels 44 and 45 with wheel 43 is illustrated in Figures 8 to 11 of the drawings.

Fig. 12 illustrates a selvage having four pairs of binding threads intertwined with weft threads 47 to 61 by a mechanism as illustrated in Figs. 4 to 11. The direction of twisting is reversed after binding—in always six weft threads: for example binding thread pairs 28, 29 and 64, 65 reverse twisting direction at the weft threads 47, 53 and 59, and binding thread pairs 62, 63 and 66, 67 reverse the direction of twisting at the weft threads 49, 55 and 61. Thread pairs 28, 29 and 64, 65 are twisted counterclockwise from weft threads 47 to 53 and clockwise from weft threads 53 to 59. Binding thread pairs 62, 63 and 66, 67 are twisted in like manner but do not reverse direction of twist at the same weft threads as pairs 28, 29 and 64, 65 which reverse direction of twist at points 68. The points where the twisting directions of thread pairs 62, 63 and 66, 67 are changed are designated by numeral 68'. The weft threads are held less firmly at the points of change of direction of twisting 68 and 68' and this is the reason why points 68 are staggered in relation to points 68'.

For obtaining a neat lateral selvage 15 with short weft thread ends the fabric is preferably cut in the direction of arrow 69, i. e. between binding thread pairs 64, 65 and 62, 63 whereby thread pairs 62, 63 and 28, 29 are separated from the fabric. The operation is similar if the twistings as per Fig. 12 are produced in the body of

the fabric and the latter is severed into two lengths as indicated by numeral 16 in Fig. 1.

For twisting threads 28, 29 about weft thread 18 the latter is first beaten by the reed 25 to the fabric 9. At this moment the twisting ring 35 is revolved 180° in the direction of arrow 70 (Fig. 2) whereby the binding thread 28 is moved from the upper shed to the lower shed to the position of thread 29. The latter is moved upward to the former position of thread 28. The position of the heddles 16 is changed at the same time from the upper shed 21 to the lower shed 22 and vice versa. This operation is repeated six times whereby ring 35 is rotated by 180° six times in the direction of arrow 70; then the direction of rotation is reversed and it is rotated six times by 180° in the direction of arrow 71 whereafter the direction of rotation is again reversed. This produces a twisting as shown in Fig. 12.

Separate drive shafts 41 and 42 are provided for the twist rings 72, 74 and 35, 73 whereby the points 68 and 68' of change of direction of the twists can be associated with different weft threads. For the same reason pinion 39 (Fig. 4) which is mounted on shaft 41 drives only two rings 72 and 74. The other two, 35 and 73, are driven by pinion 40 which is connected to and driven by shaft 42.

The actuating wheel 43 is revolved permanently in the direction of arrow 78 by pinion 76 on shaft 75 (Fig. 7) which receives power from the mechanism in box 1.

In the relative position of wheels 43 and 44 or 45 shown in Fig. 8 the roller 85 which corresponds to one of the rollers 44' or 45' in Fig. 7, 35 leaves groove 80 on the circumference of wheel 43 whereas roller 86 enters groove 81 whereby wheels 44 or 45 are revolved in the direction of arrow 88. In the position according to Fig. 9 roller 86 is about to leave curve 81 and roller 87 to enter the reversing groove 82. In the position of Fig. 10 roller 87 has entered groove 82 driving wheel 44 or 45 still in the direction of arrow 88. As soon as the reversing portion 90 of groove 82 reaches roller 87 rotation of wheel 44 or 45 is reversed to the direction of arrow 89 in Fig. 11. In the position shown in Fig. 11 roller 87 is about to leave the reversing curve 82 and roller 86 to enter curve 83. Roller 85 will enter the reversing groove 84 later and, when reaching point 90 therein, will change rotation of wheel 44 or 45 to the direction of arrow 88. The next phase is then again as illustrated in Fig. 8.

For producing different types of selvages the guide grooves on wheel 43 are machined into individual parts as designated by numerals 95 to 99 in Figs. 13 and 14 which parts are secured to the circumferential surface of wheel 43 by bolts 100. With three different shapes of the groove parts, as 95, 96 and 97, a great variety of groove configurations and consequently of twisted selvages can be obtained. The arrangement of the groove parts shown in Fig. 13' produces a twisting as illustrated in Fig. 15. Curve part 95 produces counterclockwise twisting of binding threads 28, 29 about the weft thread 47. Part 96 does not produce any twisting and threads 28, 29 bind the weft threads 48 and 49 jointly. Parts 97 and 98, if placed as in Fig. 13', produce reversal of the direction of twisting at weft thread 50 to be clockwise at thread 51.

Wheels 44 and 45 operate through wheels 46 and 46' the shafts 101 and 101' and the twist ring shafts 41, 42 respectively for rotating the twist rings 72, 74 and 35, 73, respectively. The

rollers of wheels 44 and 45 engage the grooves on wheel 43 at different points as is obvious from Fig. 7. This assures that the reversal of direction of twisting of different pairs of binding threads takes place at different weft threads; see points 68 and 68' in Fig. 12.

Both threads 28, 29 of a pair of binding threads which are twisted about one another move through the same stop motion feeler (Fig. 2). The feeler is placed where the threads 28 and 29 form a shed whereby both threads are controlled since they are alternately moved to the upper shed position by the ring 35. In the position shown in Fig. 2 thread 28 carries feeler 32 in its uppermost position. The lower binding thread 29 is so low that it cannot support the feeler if thread 28 breaks. In that case the feeler makes contact on the bar 103 whereby the loom is stopped in conventional manner.

Fig. 16 illustrates a mechanism for positively controlling a binding thread stop motion feeler 32' whereby the up and down movement of the feeler is reduced. An eccentric 104 is keyed to shaft 41 as shown in Fig. 4. A lever 105 swings about shaft 42 under the influence of the eccentric 104. The feeler 32' is adapted to ride on the free end 106 of lever 105 whereby the feeler is lifted periodically. Since the rate of speed between the shafts 41 and 42 and the discs 72, 74 and 35, 73 is two to one the feeler is lifted twice during a full revolution of said discs. It is lifted to its uppermost position when both threads 28 and 29 are at the same elevation, i. e. when their shed is closed. Thereafter the feeler is supported by the rising thread 28 and its up and down motion is much smaller than if it would rest on the binding threads all the time during a full revolution of the twisting ring 35.

The eyes 33 and 34 of the twisting rings 35, 72-74 are disposed inside their inner rims 108 for facilitating threading. This is shown in Fig. 5. Since rings 35, 73 and 72, 74 rotate in opposite directions, the eyes of rings 35, 73 and of rings 72, 74 are not in line if one turns the rings out of the position illustrated in Fig. 4, and there is room for threading because, for example, the eyes 33 of the rings 72, 74 are below the inner rims 108 of the adjacent rings 35, 73 as is obvious from Fig. 6 of the drawings.

In Figs. 17 and 18 a modified drive for the rings 35, 72-74 is illustrated whereby the rings are actuated by two spur wheels 115 and 116 rotating in opposite directions and having each in addition to teeth 113 and 114 all around, a set of teeth 125 and 126 on a part of their circumferences only. The mechanism is driven by shaft 75 which is the same as shown in Fig. 7 and which has a pinion 110 engaging wheel 111 of the concentric wheel unit 111, 112. Wheel 112 cooperates with wheel 115. The teeth of the latter engage the gear wheel 116. The additional teeth 125 and 126 of wheels 115 and 116 engage consecutively the teeth of wheels 117 and 119 which are the smaller wheels of the wheel pairs 117, 118 and 119, 120. The larger wheels 118 and 120 of these pairs engage pinions 121 and 122, respectively, which are keyed to shafts 41 and 42, respectively.

Wheels 115 and 116 rotate always in the directions indicated by arrows 123 and 124. They are provided with supplemental teeth 125, 126 on a portion of their circumference which are relatively so positioned as to drive the double tooth wheels 117, 118 and 119, 120 one after the other. In the position shown in Fig. 17 wheel 115 rotates wheel pair 117, 118 in the direction

of arrow 127 whereby shaft 41 is rotated in the direction of arrow 128. Wheel pair 119, 120 changes at this time its direction of rotation from that indicated by arrow 129 to that indicated by arrow 130. Double tooth wheel 119, 120 came to a rest after it was rotated by the toothed portion 126 of wheel 116 in the direction of arrow 129 and is rotated in the opposite direction immediately thereafter. To prevent overrotation of wheel pairs 117, 118 and 119, 120 and to effect temporary fixation in their extreme turning positions abutments and recesses 131 are provided on internal cams 136 thereon into which rollers 132 mounted at the ends of two arm levers 133 which swing about pins 134, are adapted to snap. The other ends of levers 133 are pulled together by a spring 135 whereby engagement of the rollers 132 and the cams or curves 136 is assured. The double tooth wheels 117, 118 and 119, 120 are driven alternatingly by wheels 115 and 116 for placing the points of reversal of direction of twisting, 68, 68', in Fig. 12, at different weft threads.

In the modification shown in Fig. 19 the reversing tooth wheel 115 is driven by a Geneva movement for intermittent operation of the shafts 41 and 42. Shaft 75 with pinion 110 drives wheel 136 which carries pin 137. The latter engages consecutively the radial slots 138 of wheel 139 and drives thereby stepwise the reversing wheel 115 connected with wheel 139 in the direction of arrow 123. For arresting wheel 139 during the periods when it is not engaged by the pin 137 an arresting slide 140 having an arresting pin 141 adapted to move in slots 138, is provided. Slide 140 reciprocates as indicated by double arrow 142 and is guided by guide slots 143 and 144 cooperating with stationary pin 146 and shaft 145 respectively. Slide 140 has a transverse slot 147 through which extends pin 137 and is reciprocated upon rotation of wheel 136 with pin 137. Whenever pin 137 moves out of engagement with wheel 139 arresting pin 141 enters a slot 138 and locks wheel 139.

In the modification shown in Fig. 20 the drive means for individually rotating the shedding discs by shaft 145 comprise elbow or bell crank levers 150 and 151 which are positively oscillated about stationary pins 154 and 155, respectively, in the direction of double arrows 156, 157 by means of cams 152 and 153 which are mounted on shaft 145 and respectively engaged by rollers 155 and 166 on lever 150 and rollers 167 and 168 on lever 151. The oscillating movement of levers 150 and 151 is transferred by tooth gears 158, 160 and 159, 162 to double tooth wheels 160, 161 and 162, 163, respectively, and therefrom to pinions 121 and 122, respectively, of shafts 41 and 42. Shaft 145 may be driven intermittently in the direction of arrow 123 by the Geneva gear shown in Fig. 19. Wheel 136 and the slotted wheel 139 are shown in dash-dot lines in Fig. 20. Shaft 145 may also be driven continuously.

In the operating position shown in Fig. 20 lever 151 changes its movement from that indicated by arrow 169 to that of arrow 170 whereby the rotation of shaft 42 is reversed from arrow 171 to 172. Lever 150 moves in the direction of arrow 173 and shaft 41 rotates in the direction of arrow 174. Due to the relatively displaced positions of levers 150 and 151 reversal of rotation of shafts 41 and 42 does not occur at the same time.

In the modification shown in Figs. 21 to 23 the main shaft 176 is driven by shaft 75 (Fig. 7) by means of toothed gearing 177, 178 (Fig. 23).

Shaft 176 carries reversing wheels 179 and 180, each being provided with teeth 181 and 182, respectively, at only one half of its circumference. Teeth 181 and 182 engage consecutively pinions 184, 183 and 185, 186. Pinion 183 is fast on shaft 41 and shaft 42 is fast on wheel 187 which is driven by pinion 186.

The main shaft 176 rotates wheels 179 and 180 in the direction of arrow 188. In the position 10 shown in Fig. 21 wheel 180 engages pinion 186 which is rotated in the direction of arrow 189 and which rotates pinion 187 and therewith shaft 42 in the direction of arrow 190. Pinion 184 idles in the direction of arrow 191.

In the position illustrated in Figs. 22 and 23 wheel 180 is out of engagement with pinion 186 and wheel 179 drives pinion 184 in the direction of arrow 192. Pinion 186 is rotated in the direction indicated by arrow 193 and shaft 42 rotates in the direction of arrow 194, i. e. in a direction opposite to that of the operating phase shown in Fig. 21.

Wheel 179 drives pinion 183 in the direction of arrow 194 whereas pinion 185 idles in the direction of arrow 195. As soon as the end 196 of the toothed portion 181 of wheel 179 has reached pinion 183, the toothed portion 182 of wheel 180 engages pinion 185 and operates it in the direction of arrow 197 whereby rotation of pinion 183 is reversed to the direction indicated by arrow 198.

If staggering of the points of reversal of direction of rotation of the twisting operation is not required, i. e. if the twisting of several individual groups of binding threads is reversed at the same weft threads only one twist ring drive shaft 200 is required as shown in Fig. 24.

The method and means according to the invention can be used in connection with gripper shuttle looms as well as with conventional bobbin shuttle looms, in the latter case they are particularly advantageous for making twisted weavings in the body of the fabric where it can be cut leaving a firm selvage.

By operating a plurality of twisting heads side by side and cutting the weft threads between groups of twisted binding threads a new kind of chenille can be produced. If weft threads of different colors are inserted by a multiple thread supplier, patterned chenille may be obtained.

While I believe the above described embodiments of my invention to be preferred embodiments, I wish it to be understood that I do not desire to be limited to the exact details of method, design and constructions shown and described, 55 for obvious modifications will occur to a person skilled in the art.

I claim:

1. The method of binding weft threads in looms for weaving by means of groups of binding threads guided to move substantially in the same direction as the warp threads, including the steps of twisting the binding threads of individual groups about one another between weft threads, and reversing the direction of rotation of the 60 twists after binding-in a plurality of weft threads the reversing step for different groups of binding threads being effected at different weft threads.

2. In a loom for weaving, the combination of a loom drive, a pair of binding threads guided to move substantially in the direction of the warp threads, twisting means through which said binding threads extend and periodically forming a 65 shed of said binding threads and twisting same about one another between weft threads, a mechanism connected to and operated by said loom

drive and connected to and actuating said twisting means, a binding thread stop motion feeler adapted to ride on the upper thread of the binding thread forming a shed, and feeler support means having a portion so located that said feeler rides thereon when the shed formed by the binding threads is closed.

3. In a loom for weaving, the combination of a loom drive, a pair of binding threads guided to move substantially in the direction of the warp threads, twisting means through which said binding threads extend and periodically forming a shed of said binding threads and twisting same about one another between weft threads, a mechanism connected to and operated by said loom drive and connected to and actuating said twisting means, a binding thread stop motion feeler adapted to ride on the upper thread of the binding thread forming a shed, and a movable feeler support means connected to and reciprocatingly moved up and down by said drive means and having a portion supporting said feeler when said support means is in the upper position.

4. In a loom for weaving, the combination of a loom drive, a pair of binding threads guided to move substantially in the direction of the warp threads, a rotatable twisting means having eyes through which said binding threads pass individually and causing said threads to periodically form a shed and to be twisted about one another between weft threads, a rotatable actuating means connected to and rotated continuously by said loom drive, said actuating means comprising curved guide means, roller means adapted to engage and to be guided and displaced by said guide means upon rotation of said actuating means, and a toothed gear mechanism interconnecting said roller means and said twisting means and rotating the latter upon displacement of the former.

5. In a loom for weaving as defined in claim 4, said guide means having such configuration as to periodically reverse the direction of rotation of said twisting means.

6. In a loom for weaving as claimed in claim 4, said actuating means having the configuration of a wheel having a rim portion and said guide means being composed of a plurality of individual members disconnectably connected with said rim portion.

7. In a loom for weaving having a loom drive, a mechanism for binding-in weft threads by means of a plurality of groups of binding threads guided to move substantially in the direction of the warp threads, said mechanism comprising a plurality of rotatable twisting means, each twisting means having eyes through which the binding threads of one group pass individually and causing said binding threads to periodically form a shed and to be twisted about one another between weft threads, a rotatable actuating means connected to and rotated continuously by said loom drive, said actuating means comprising curved guide means, a plurality of mechanisms comprising roller means engaging and being guided and displaced by said guide means and being individually connected with an individually rotating said twisting means upon displacement of said roller means.

8. In a loom for weaving having a loom drive, a mechanism for binding-in weft threads by means of a plurality of groups of binding threads guided to move substantially in the direction of the warp threads, said mechanism comprising a

plurality of rotatable twisting means, each twisting means having eyes through which the binding threads of one group pass individually and causing said binding threads to periodically form a shed and to be twisted about one another between weft threads, an actuating gear wheel connected to and rotated continuously by said loom drive, a pair of double gear wheels comprising gear wheels continuously engaging one another and one engaging and being rotated by said actuating wheel, each of said double gear wheels having a partly toothed gear wheel, and toothed gear drives periodically individually engaged and rotated by said partly toothed gear wheels and individually connected to and periodically rotating said twisting means.

9. In a loom for weaving as defined in claim 8, said double gear wheels rotating in opposite directions.

10. In a loom for weaving having a loom drive, a mechanism for binding-in weft threads by means of a plurality of groups of binding threads guided to move substantially in the direction of the warp threads, said mechanism comprising a plurality of rotatable twisting means, each twisting means having eyes through which the binding threads of one group pass individually and causing said binding threads to periodically form a shed and to be twisted about one another between weft threads, an actuating gear wheel connected to and rotated continuously by said loom drive, a plurality of partly toothed gear wheels connected to and rotated by said actuating wheel, and a plurality of trains of toothed gears comprising gear wheels periodically individually engaged and rotated by said partly toothed gear wheels and connected to and individually periodically rotating said twisting means.

11. In a loom for weaving having a loom drive, a mechanism for binding-in weft threads by binding threads guided to move substantially in the direction of the warp threads, said mechanism comprising rotatable twisting means having eyes through which the binding threads pass individually and causing said binding threads to periodically form a shed and to be twisted about one another between weft threads, and a drive mechanism comprising a cam connected to and rotated by said loom drive, a lever having an arm engaged and actuated by said cam for oscillating said lever and having another arm, and a rack on said other arm, a spur gear transmission engaged by said rack and connected to and operating said twisting means in accordance with the motions of said lever.

12. In a loom for weaving having a loom drive, a mechanism for binding-in weft threads by binding threads guided to move substantially in the direction of the warp threads, said mechanism comprising rotatable twisting means having eyes through which the binding threads pass individually and causing said binding threads to periodically form a shed and to be twisted about one another between weft threads, and a drive mechanism comprising a Geneva movement connected to and rotated by said loom drive, a shaft connected to and intermittently rotated by said Geneva movement, a cam fixed on said shaft, a lever having an arm engaged and actuated by said cam for oscillating said lever and having another arm, and a rack on said other arm, a spur gear transmission engaged by said rack and connected to and operating said twisting means in accordance with the motions of said lever.

13. In a loom for weaving having a loom drive, a mechanism for binding-in weft threads by binding threads guided to move substantially in the direction of the warp threads, said mechanism comprising rotatable twisting means having eyes through which the binding threads pass individually and causing said binding threads to periodically form a shed and to be twisted about one another between weft threads, and a drive mechanism comprising a shaft connected to and rotated by said loom drive, a spur gear wheel connected to and rotated by said shaft, another spur gear wheel driven by said first spur gear wheel, a pin axially extending from the second gear wheel, a second shaft, a Geneva cross mounted on said second shaft and having recesses adapted to be engaged by said pin, a member reciprocatingly slideable on said second shaft in a direction transverse to the longitudinal axis of said second shaft and having a slot disposed transversely to the direction of the reciprocating movement of said member, said pin extending through said slot for imparting a reciprocating movement to said member upon rotation of said spur gear wheels, guide means for said member assuring an exclusively reciprocating movement thereof, an arresting pin mounted on said member and adapted to engage a recess on said Geneva cross upon movement of said member to one extreme position, for preventing rotation of said cross when said pin on said other spur gear wheel is out of engagement with said Geneva cross, said arresting pin sliding out of engagement with said Geneva cross upon movement of said member to its other extreme position and when said pin on said spur gear engages said Geneva cross, and a drive mechanism connected to said second shaft and to and operating said twisting means in accordance with the motions of said Geneva cross.

14. In a loom for weaving as defined in claim 13, said drive mechanism comprising a pair of gear wheels one of which being connected to and rotated with said Geneva cross, a partly toothed gear wheel concentrically attached to each gear wheel of said pair, and a pinion adapted to be alternately engaged by said partly toothed gear wheels and connected with and operating said twisting means.

15. In a loom for weaving having a loom drive, a mechanism for binding-in weft threads by binding threads guided to move substantially in the direction of the warp threads, said mechanism comprising rotatable twisting means having eyes through which the binding threads pass individually and causing said binding threads to periodically form a shed and to be twisted about one another between weft threads, and a drive mechanism comprising a gear wheel connected to and rotated by said loom drive, a second gear wheel engaged by the first gear wheel and rotating in opposite direction, a partly toothed gear wheel concentrically connected with each of said gear wheels, a third gear wheel adapted to be alternately engaged by the teeth of the partly toothed gear wheels for alternate rotation in opposite directions, and arresting means connected with said third gear wheel for arresting it before its direction of rotation is reversed.

16. In a loom for weaving as defined in claim 15, said arresting means comprising a cam having a recess, a cam follower resiliently pressed to said cam and adapted to snap into said recess

for resisting rotation of the cam at the desired moments.

17. In a loom for weaving having a loom drive, a mechanism for binding-in weft threads by binding threads guided to move substantially in the direction of the warp threads, said mechanism comprising rotatable twisting means having eyes through which the binding threads pass individually and causing said binding threads to periodically form a shed and to be twisted about one another between weft threads, said twisting means comprising a frame having a circular opening and an annular recess around said opening, a shedding ring disposed in said recess and having ear portions at its inner side and projecting into said opening, said eyes being placed in said ear portions and accessible through said opening for threading, and a drive mechanism connected to and operated by said loom drive and engaging the outer side of said shedding ring for rotating said ring.

18. In a loom for weaving having a loom drive, a mechanism for binding-in weft threads by binding threads guided to move substantially in the direction of the warp threads, said mechanism comprising rotatable twisting means having eyes through which the binding threads pass individually and causing said binding threads to periodically form a shed and to be twisted about one another between weft threads, said twisting means comprising a frame having a circular opening and bearing means surrounding said opening, a shedding ring disposed in said bearing means and having ear portions at its inner side and projecting into said opening, eyes in said ear portions and accessible through said opening for threading, teeth at the outside of said ring, a pinion disposed in said frame and engaging said teeth, and a drive mechanism connected to and operated by said loom drive and connected to and rotating said pinion.

19. In a loom, the combination of a rotating shaft, a plurality of warp shedding discs having toothed rims, individual drive means operatively connected with said shaft and said discs for individually rotating the discs in either direction, said means comprising a lever, a cam fixed on said shaft and being engaged by said lever and actuating said lever, said lever having an arcuate and toothed surface portion concentric with its fulcrum, and a train of gear wheels interposed between said arcuate surface portion and said discs.

20. In a loom as defined in claim 19, said lever having the configuration of a bell crank engaging said cam with one arm and having said toothed surface portion on the other arm.

21. In a loom, the combination of a plurality of warp shedding discs, means operatively connected with said discs for rotating them in either direction, said means comprising a rotating shaft, pairs of substantially like cam members fixed on said shaft, an elbow lever associated with each pair of cam members, a cam follower roller mounted on each arm of said lever, one roller engaging one cam member and the other roller engaging the other cam member of the same pair, and a mechanism interposed between said lever and said discs for actuating said discs in a manner determined by the configuration of said cams.

22. In a loom, the combination of a plurality of warp shedding discs, means operatively connected with said discs for rotating them in either direction, said means comprising a rotating shaft,

13

pairs of substantially like cam members fixed on said shaft, two elbow levers associated with each pair of cam members, a cam follower roller mounted on each arm of said levers, one roller engaging one cam member and the other roller engaging the other cam member of the same pair, and a mechanism interposed between said levers and said discs for actuating said discs in a manner determined by the configuration of said cams.
